ATTORNEY

UNITED STATES PATENT OFFICE.

ORA A. COLBY, OF IRWIN, PENNSYLVANIA, ASSIGNOR TO WESTINGHOUSE ELECTRIC & MANUFACTURING COMPANY, A CORPORATION OF PENNSYLVANIA.

ELECTRIC RADIANT HEATER.

Application filed May 24, 1923. Serial No. 641,061.

To all whom it may concern:

Be it known that I, ORA A. COLBY, a citizen of the United States, and a resident of Irwin, in the county of Westmoreland and

5 State of Pennsylvania, have invented a new and useful Improvement in Electric Radiant Heaters, of which the following is a specification.

My invention relates to electrical heating 10 devices and particularly to electric air heaters.

One object of my invention is to provide an electric air heater of relatively simple structure and of relatively large distributed 15 capacity.

Another object of my invention is to provide an electric air heater comprising a plurality of independent heating elements.

Another object of my invention is to provide 20 an electric air heater comprising a plurality of independent heating elements, each element comprising a skeleton frame having a plurality of spaced, parallel-extending bars on which a resistor member is located.

25 Another object of my invention is to provide a heating element comprising a refractory supporting means of such form as to provide relatively small heat storage capacity and effective to support a substantially uniformly distributed radiant resistor member.

In practicing my invention, I provide a suitable casing having a front opening therein, and a plate of refractory electric-insulating material in said casing back of 35 said front opening.

I provide a plurality of skeleton frames, of refractory electric-insulating material, each frame comprising a plurality of 40 spaced, parallel-extending bars. A helically wound resistor member is wound in helical convolutions upon the respective bars of the skeleton frames that may be provided with integral spaced lugs or bosses to separate 45 the adjacent turns of the resistor member on the individual bars, from each other.

I provide a suitable switch to control the energization of the heating elements, such switch being located on the outside of said 50 casing.

In the single sheet of drawings,

Figure 1 is a view, in front elevation, of an electric air heater comprising the device embodying my invention,

Fig. 2 is a view, in vertical lateral section 55 therethrough, taken on the line II—II of Fig. 1,

Fig. 3 is a partial view, in front elevation, of a modified form of device embodying my invention,

Fig. 4 is a view, in vertical lateral section 60 therethrough, taken on the line IV—IV of Fig. 3,

Fig. 5 is a partial enlarged view, in front elevation, of a heating element comprising 65 a refractory skeleton frame and a resistor member located thereupon, and

Fig. 6 is a partial enlarged sectional view 70 through one of the supporting bars of the skeleton frame illustrated in Fig. 5, showing particularly the integral bosses located thereon.

An electric air heater 11 comprises a casing 12 that may be built up in any suitable or desired manner, either by the use of sheet metal members or by the use of metal castings combined to form a casing having an ornamental and pleasing appearance. The casing 12 may be located on a base 13 having integral supporting members 14. 75

A cover member 15 is provided that may be removable from the rest of the casing to permit of mounting the other parts of the heater therein. The top or cover member 15 is of such form and construction as to harmonize with the casing 12. 80

The casing 12 is provided with a depressed front portion 16 having an opening 17 therein. A grating 18 is provided in the depressed portion 16 and comprises a plurality of vertically and of horizontally extending rods or wires suitably secured together to constitute a skeleton frame. 90

The upper ends of the vertically extending bars are loosely fitted into a plurality 95 of spaced and co-operating openings 19 in the top part of the depressed portion 16. A plurality of spaced openings 21 is provided in the lower part of the depressed portion 16 into which the lower ends of the 100

vertically extending rods may fit loosely, a horizontally extending rod 22 secured to the grating being provided to suitably locate the grating in the respective openings 19 and 21. The length of the vertically extending rods or wires is such that the grating may be mounted in its proper operative position by first placing the upper ends thereof in the cooperating openings 19, then 5 raising the grating a sufficient amount to permit of the lower ends entering the lower openings 21, whereupon the grating is permitted to drop to its proper operative position substantially as illustrated in Figs. 2 10 and 4 of the drawing.

A plate 23, of a suitable refractory electric insulating material which is provided within the casing 12, constitutes a reflector for the heating elements to be hereinafter 20 described. The plate 23 is held in its proper operative position back of the front opening 17 by any suitable means, such as a refractory plate or bar 24 located therebeneath. Any suitable or desired means may be provided for holding the plate 24 in substantially 25 the position illustrated in the drawings.

A plurality of heating elements are located in the casing in front of the reflector 30 plate 23 and severally comprise a skeleton frame 25 of refractory electric-insulating material and a helically wound resistor member 26. Each of the skeleton frames comprises integral end portions 27 and side 35 portions 28 constituting a rectangular frame. A plurality of spaced bars 29 integral with the ends 27 extend longitudinally of the skeleton frames 25 that are substantially rectangular in contour and that 40 may be of any suitable or desired width and length.

The integral bars 29 are each provided on one surface thereof, for instance at the 45 front of the frames 25, with a plurality of spaced integral bosses 30. The helically wound resistor members 26 are helically wound on the respective bars 29, the bosses 30 serving to insulate adjacent turns of the resistor member from each other, or in 50 other words, to maintain the adjacent turns in a predetermined position on the bars and relatively to each other.

As illustrated in Fig. 1, the skeleton frames may be so supported in front of the 55 reflector plate 23 that the bars 29 extend in a substantially horizontal direction. If desired, the skeleton frames 25 may, however, be so located in the casing that the bars 29 extend in a substantially vertical 60 direction, as illustrated more particularly in Fig. 3 of the drawing. A plurality of openings 31 may be provided at the corners of the skeleton frames to permit of securing them against the reflector plate.

65 The dimensions of the helical resistor

member 26 and of the bars 29 and the spacing between the adjacent turns of the respective supporting bars 29 are such that substantially uniformly distributed heating units are obtained and any desired relative location of the turns of the resistor member on the adjacent supporting bars may be employed to still further distribute the winding over the available surface.

Any desired number of resistor members 70 26 may be employed not only in accordance with the voltage of the supply circuit to which the electric heater embodying my invention is to be connected, but also in accordance with the method of control of the 75 individual heating units.

A means for controlling the supply of energy to the heating elements may comprise a switch 32 that is suitably secured against a face plate 33 which is, in turn, 80 suitably secured against a side portion of the casing 12 by a plurality of screws 34. A pair of bus bars 35 and 36 may be suitably mounted in the casing 12 in either a substantially vertical position, as illustrated 85 in Figs. 1 and 2 of the drawing, or in a substantially horizontal position, as illustrated in Figs. 3 and 4 of the drawing and be suitably supported therein.

The ends of the individual heating units 90 26 may be made sufficiently long to permit of their being secured to the respective bus bars 35 and 36 by suitable means, such as machine screws 37. Terminal pins 38 may be mounted on the plate 33 of electric-insulating material to permit of easily and quickly connecting the terminals of a supply circuit, not shown, thereto. The terminal pins 38 are suitably connected to the control switch 32 and to the bus bars 35 and 36 to 100 permit of suitably controlling the supply of energy to the individual heating units.

The device embodying my invention thus provides a plurality of relatively simple and compact individual heating units that 110 may be easily and quickly removed from and replaced in their proper operative position and that severally provide a heating element comprising a substantially uniformly distributed heating unit located 115 therein.

Various modifications and changes may be made without departing from the spirit and scope of the invention and I desire, therefore, that only such limitations shall be placed thereon as are imposed by the prior art or are set forth in the appended claims.

I claim as my invention:

1. In an electric heater, in combination, 120 a casing having an open front, a reflector plate, of refractory material, in said casing adjacent said open front, and a plurality of radiant heating elements in said casing in said open front, each heating element comprising a refractory skeleton frame having 125 130

a plurality of spaced, parallel, bars, and a helical resistor member helically wound on said bars.

2. In an electric heater, in combination,
5 a casing having an open front, a reflector plate, of refractory material, in said casing adjacent said open front, and a plurality of radiant heating elements in said casing in said open front, each heating element
10 comprising a refractory skeleton frame

having a plurality of spaced, parallel, bars, each of said bars having integral, spaced, lugs thereon and a helical resistor member helically wound on said bars between said lugs.

In testimony whereof, I have hereunto subscribed my name this 21st day of May, 1923.

15

ORA A. COLBY.
